GAUGING OF ARTICLES FOR DIAMETER

Theodore A. Jagen, Harrison, N. J., assignor to
 General Motors Corporation, Detroit, Mich., a
 corporation of Delaware

Application March 11, 1947, Serial No. 733,879

14 Claims. (Cl. 209—88)

1

This invention relates to the gauging of articles for diameter and is herein shown as embodied in a machine for gauging cylindrical rollers and separating those of acceptable size from the others. The chief object is to provide an improved gauging and segregating machine which will gauge rollers with great speed and reliability. To this end and also to improve generally upon machines of this character, the invention consists in the various matters hereinafter described and claimed. In its broader aspects the invention is not necessarily limited to the specific construction selected for illustration in the accompanying drawings in which

Fig. 1 is a plan view, the gauging head being broken away.

Fig. 2 is an end view, the selector arm and its actuating means being removed.

Fig. 3 is a side view, a solenoid being removed.

Fig. 4 is a side view with some parts removed and some in central section.

Fig. 5 is a plan view of the base with a separator blade added.

Fig. 6 is a perspective view of a portion of the base.

Fig. 7 is a perspective view of parts adjacent to the selector arm which is shown swung to one side, one of the side guides being backed away.

Fig. 8 is a view similar to Fig. 7 but showing additional elements the selector arm being in central position.

Fig. 9 is a view similar to Fig. 8 with some elements added.

Fig. 10 is a perspective view of some of the elements of Fig. 7 as seen from the opposite side.

Fig. 11 is a perspective view of the selector as seen from below.

Fig. 12 is a diagram.

First outlining briefly the general operation, the articles to be gauged for diameter and accepted or rejected are herein shown as cylindrical rollers with slightly rounded ends. They are urged endwise in a stream toward a tiltable selector having article receiving grooves on opposite sides of a central rib, the rib first acting as a stop while the endmost roller is under a movable gauge stem and held down by a shoe while confined at the bottom and sides by hardened guides. Depending on the diameter, the selector swings to one side or the other by action of a solenoid and the gauged roller moves endwise into one of the grooves and, when the selector swings back to central position, the roller is dropped down on one side or the other of a narrow blade or separator located immediately below

2

the center line of the selector. Acceptable rollers drop on one side of the blade and rollers that are too large or too small drop on the other side.

The rollers R are urged endwise in a stream under considerable pressure by any suitable feeder leading to a feed tube 2 secured by a clamping screw 4 to a clamping member 6 whose hub is secured by a screw to a raised block 8 at one end of a base 10. The endmost roller and a following one slide out of the tube onto a hardened insert in the center of a plate 12 set in a groove 14 in the raised block. This block is also grooved lengthwise to receive tongues on a pair of side guides 16 which are slotted for adjustable clamping by screws 18. The side guides also have hardened inserts at their adjacent ends to guide the roller laterally. The endmost roller is first stopped by the end of a central rib 20 on the bottom of a grooved selector 22 having a roller receiving groove 24 on each side of the rim. When a roller enters one of the grooves it is stopped by a plate 25 fastened to the selector.

The selector 22 is fastened to the bottom of a tiltable selector arm 26 of little mass and having vertical stiffening webs and a vertical hub portion 28 which is journaled on balls Fig. 3 engaging conical recesses in the hub portion and in upper and lower adjusting screws 32, the upper screw being adjustable vertically in an angle bracket 34 secured to a slide 36. The slide is adjustably secured to the base by screws 38 passing through slots. Endwise location of the slide is determined by adjustable stop screws 40 threaded in the raised block 8. As indicated in Figs. 2 and 4, the bottom of the slide has a pair of locating keys 42 entering a slot in the base.

The arm 26 is pivotally connected to the plungers 44 of two solenoids 46 and 48 suitably mounted on the slide. To urge the selector arm to a central position and dampen vibration, a spring 40 pressed headed plunger 50 is mounted on each side of it to slide in an angle bracket 52 adjustably secured to the slide. As indicated in Fig. 8, the head of each plunger is engaged by a coil spring 54 backed up by an adjusting screw 56. The head of each plunger slides in a hole in the angle bracket and when it is stopped by the end wall of the hole, the other end of the plunger is very slightly spaced from the selector arm as indicated in Fig. 1.

As indicated best in Figs. 2 and 8, the foremost roller in gauging position and a following roller are held down on the supporting plate 12 by a shoe 58 secured by screws to the end of a spring pressed lever 60 pivoted at 62 in an opening of a standard 64, the rear arm of the lever

being connected to a tension spring 66 whose tension is adjustable by a screw 67. The lever is slotted to allow access to screw 18. Immediately ahead of the hold-down shoe the foremost roller is engaged by a gauging plunger 68 projecting downwardly from a gauging head 70 mounted on a vertical slide 72 which is adjustable vertically on the standard 64 by a screw 14. The diagram hereinafter described indicates how segregation is controlled by the gauge.

Referring to Figs. 4, 5, 6 and 10, the base 10 has two openings 76 on each side of a central partition or reinforcing web 78 which is bevelled at the top and joins a cross web below the block 8. Immediately above the partition is a thin blade or separator 80 having two rounded securing lugs, an upper lug 82 being fastened in a recess in the block 8 and a lower lug 84 being fastened in a recess in the base. This blade or separator lies immediately under the center line of the selector 22 with its upper edge on a level with the plate 12 and extending close up to the rear of the guide plate 12 to support the rollers when they advance into the selector. The forward end of the selector (Figs. 1 and 11) is arcuate with the center of curvature at the pivotal axis of the selector arm. The two grooves 24 in the selector are at a small angle to one another so that they will line up with the stream of rollers whenever the selector is swung to one side. The angular movement is small and each groove 24 is just long enough to receive a roller. When a roller enters the groove, the following rollers in the stream are first held back by the entered roller and then by the central rib 20 as the selector swings back to central position.

Referring to the diagram, the gauging head 70 is connected by lines 81 to an electronic amplifier 82, these units being commercially available, the unit 82 containing a switch 83 which can be set to close only when a gauged article under the gauge plunger is either oversize or undersize and to open only if the article is acceptable. Lines 84 and 85 supply power to energize several circuits, including the amplifier unit 82 and a repeat cycle timer 86, line 84 being common to the last two members and also to relays A, B and C, and to the two solenoids 46 and 48. The timer is a commercial unit having a switch 87 that repeatedly closes and opens with great rapidity (say 300 times a minute) both "on" and "off" periods being adjustable and the sum of the two periods determining the cycle of gauging and discharging one article. The optimum repetition rate is governed by the speed with which the articles can be fed axially in a stream to the gauge and transferred to the selector and ejected.

With an acceptable roller under the gauge head spindle and the roller selector in its central position with the stream of rollers halted by the central rib 20, the switch 83 of the amplifier is in open position as previously set by a master and, assuming the rapidly operated switch 87 of the timer is then open for an instant but about to close, none of the relays or the solenoids will be energized because line 85 is disconnected from them. A very small fraction of a second later the timer switch 87 closes so that current flows through a line 88, across a switch 89 to a line 90, across a switch 91 to a line 92 and then branching to solenoid 46 and to relay C and back through the common line 84. When solenoid 46 is thus energized it moves the selector to line up the left hand groove with the stream of rollers and when relay C is thus energized, its switch 94 opens

so that the gauging circuit is rendered ineffective for an instant while the transfer part of the cycle occurs during which the gauged roller advances (by axial pressure on the stream) into the left hand groove of the selector while another following roller advances under the gauge head spindle 68. Solenoid 46 and relay C are immediately de-energized by the opening of the rapidly operating timing switch 87. If the following rollers are acceptable, switch 83 will remain open and the solenoid 46 will be energized every time the timing switch closes. All such acceptable rollers will drop down at the left of the blade 80 on the return of the selector to central position.

If the roller following the acceptable roller is not acceptable, it will cause the amplifier switch 83 to close as the latter is set to do but ineffectively because of the opening of the switch 94 when relay C is energized during the action of solenoid 46 in selecting the preceding acceptable roller. Hence the gauging circuit is rendered ineffective for an instant and cannot be affected by this following unacceptable roller during the short time the gauged and acceptable roller is advancing into the selector and being ejected, the ejection occurring when the solenoid 46 is de-energized to allow the selector to return to central position.

Assuming an unacceptable roller, oversize or undersize, in gauging position under the gauge head spindle 68, the amplifier switch 83 will close as it is set to do for such a roller. Assuming the timing switch 87 is open but about to close, the relay C cannot be energized and so its switch 94 will be closed and cause energizing of the relay A. Hence the relay switch 89 will be pulled down to connect line 88 to a line 95 leading to solenoid 48 and branching to relay B. When rapidly operating timing switch 87 closes, solenoid 48 and relay B are energized, the solenoid swinging the selector to the left to receive the unacceptable roller in the right hand groove after which the return of the selector to central position drops the unacceptable roller to the right of the blade. Energizing of relay B opens the switch 91 and closes a switch 96 to make a direct connection from line 88 to line 95 so that even if relay A be de-energized (as by a following acceptable roller opening the amplifier switch 83) there will be established a holding circuit for solenoid 48 and relay B for the very short period that the unacceptable gauged roller is being transferred from under the gauge head spindle to the selector.

The transfer portion of the cycle always occurs when the timing switch 87 is closed because that is the only time either of the solenoids can be energized to swing the selector to receive a roller in one of its pockets. Viewing the diagram, when the right hand solenoid 46 is energized, an acceptable roller is received in the left hand groove and ultimately dropped on the left side of the center and when the left hand solenoid 48 is energized, an unacceptable roller is received in the right hand groove and ultimately dropped on the right side of the center. The machine is readily adapted to gauge rollers of different sizes, the side guides being spread apart for larger rollers and the selector being replaceable by another having grooves of proper length, width and depth.

I claim:

1. In apparatus of the character indicated, means providing a gauging station from which rollers are successively pushed endwise, a gauging member to engage each roller at the gauging

5

station, a selector having a roller receiving pocket, a rib at one side of the pocket and located in the path of the roller during gauging to locate the pocket normally out of line with the gauging station, a shiftable arm controlled by the gauging member when the roller is of a predetermined size, said arm shifting the rib from the path of the rollers to bring the pocket in line with the gauging station for receiving a roller endwise, and mechanism returning the rib to its original position after each gauging operation and causing the gauged roller to be carried out of line with the gauging station and discharged.

2. In apparatus of the character indicated, means providing a gauging station from which rollers are successively pushed endwise, a gauging member to engage each roller, a selector having a rib normally in line with the gauging station, gauging member for controlled mechanism shifting the selector and its rib to one side of said gauging station for acceptable rollers and to the other side for unacceptable ones, the selector having a roller receiving recess on each side of the rib to receive the roller, and the rib pushing the roller laterally to a discharge position when the selector returns to central position.

3. In apparatus of the character indicated, means providing a gauging station through which the rollers are urged endwise in a stream, a gauging member engaging the endmost roller, a selector having a central stop rib to stop the roller for gauging, means controlled by the gauging member for shifting the selector and its stop rib to one side for acceptable rollers and to the other side for unacceptable ones, the selector having a roller receiving pocket on each side of the stop rib to receive the roller when the stop rib is shifted to one side, and means at the end of each pocket for arresting the entered roller with its trailing end substantially flush with the end of stop rib, and means for returning the selector to normal position to discharge the roller.

4. In apparatus of the character indicated, means providing a gauging station through which rollers are urged in a stream, a gauging member engaging the endmost roller, a selector having a central stop rib to stop the roller for gauging, means controlled by the gauging member for shifting the selector and its stop rib to one side for acceptable rollers and to the other side for unacceptable ones, the selector having a roller receiving pocket on each side of the stop rib to receive the roller and carry it laterally out of the stream when the selector returns to central position, and means on each side of the selector for urging it to a central position.

5. In apparatus of the character indicated, means providing a gauging station from which rollers are successively pushed endwise, a gauging member to engage each roller, a selector having a central rib in line with the path of advance of the rollers, a separator blade below the rib to support the roller when it advances from the gauging station, means controlled by the gauging member for shifting the selector and its central rib to one side for acceptable rollers and to the other side for unacceptable ones, and the selector having a roller receiving pocket on each side of the central rib for shifting the roller laterally off the blade when the selector returns to central position.

6. In apparatus of the character indicated, means providing a gauging station through which rollers are urged in a stream, a gauging member engaging the endmost roller, a selector

6

having a central rib in line with the gauging recess to stop the roller, a separator blade below the rib to support the gauged roller when the rib is shifted laterally out of line with the gauging recess, means controlled by the gauging member for shifting the selector and its stop rib to one side for acceptable rollers and to the other side for unacceptable ones, and the selector having a pocket on each side of the stop rib to receive and stop a gauged roller when advanced onto the blade.

10 7. In apparatus of the character indicated, means providing a gauging station from which rollers are successively pushed endwise, a gauging member to engage each roller, a separator blade in line with the stream of rollers to support a gauged roller when advanced beyond gauging position, a selector mounted above the blade and having a central rib normally in line with the gauging station, the selector also having a pair of downwardly open grooves to receive rollers selectively in accordance with the size, and means for oscillating the selector and its central rib to advance a roller into a selected groove and push it laterally off the blade.

15 8. In apparatus of the character indicated, means providing a gauging station through which rollers are urged in a stream, a gauging member engaging the endmost roller, a separator blade in line with the stream of rollers to support a gauged roller when advanced beyond gauging position, a selector mounted above the blade and having a central stop rib to arrest each roller in gauging position, the selector also having a pair of downwardly open grooves to receive rollers selectively in accordance with the size, a pair of solenoids having connection with opposite sides of the selector, means controlled by the gauging member for determining which solenoid will be energized to shift the selector laterally and advance a gauged roller into the selected groove, and means for returning the selector to central position to discharge the roller to the selected side of the blade.

20 45 9. In apparatus of the character indicated, means providing a gauging station from which rollers are successively pushed endwise, a gauging member to engage each roller, a separator blade in line with the stream of rollers, a selector mounted above the blade and having a pair of roller receiving pockets on opposite sides of the center, a pair of solenoids connected to opposite sides of the selector, means controlled by the gauging member for energizing a selected solenoid to shift the selector to one side when the roller is of acceptable size and to shift the selector to the other side when the roller is of unacceptable size, and means for urging the selector to central position to push the roller laterally off the blade to the selected side thereof.

25 50 55 60 65 70 75 10. In apparatus of the character indicated, a gauge having a work engaging member to control an electronic amplifier, a selector to receive work pieces successively from the gauge, a laterally movable rib on the selector and stopping the entrance of a work piece into the selector during each gauging operation, a pair of solenoids connected to the selector to shift the rib to a selected side of the gauge for segregating the work pieces into two classes, a repeat cycle timer having a switch which rapidly closes and opens one of a pair of preselected solenoid circuits, and the electronic amplifier having a switch controlled by the size of the work pieces to determine which of the

solenoid circuits will be completed by the action of the timing switch.

11. In apparatus of the character indicated, a gauge having a work engaging member, an electronic amplifier having a switch controlled by the work engaging member to open or close depending on work size, a selector to receive work pieces from the gauge and segregate them into two classes, the selector having a laterally movable rib normally stopping the advance of a work piece into the selector during a gauging operation, a pair of solenoids to actuate the rib, a repeat cycle timer wired to the solenoids and having a switch rapidly opening and closing a preselected circuit to one of the solenoids when the gauged work is of a size acceptable for one class, and a relay energized by the action of the amplifier for switching the repeat cycle timer into circuit with the other solenoid to rapidly open and close the circuit to said other solenoid when the gauged work is of a different size for the other class.

12. In apparatus of the character indicated, a gauge having a work engaging member, an electronic amplifier having a switch controlled by the work engaging member to open or close depending on work size, a selector to receive work pieces from the gauge, said selector having a laterally movable rib normally stopping movement of a work piece into the selector during a gauging operation, a pair of solenoids connected to the selector to laterally shift the rib to selected sides of the gauging member to segregate the work pieces into acceptable and unacceptable sizes, a repeat cycle timer having a rapidly opening and closing switch in the solenoid circuits to energize the solenoids selectively, a relay switch controlled by the amplifier switch to determine which solenoid circuit will be rapidly energized and deenergized by the action of the repeat cycle timer switch, and means for rendering the gauge temporarily ineffective after either solenoid is energized.

13. In apparatus of the character indicated, a gauging head and an electronic amplifier therefor, a work engaging member to control the

amplifier, a selector provided with a rib between a pair of pockets arranged to receive work pieces from the gauge, said rib being normally in line with a work piece being gauged to stop work piece advance, mechanism for shifting the rib in two directions selectively to segregate the work into two classes, a repeat cycle timer having a rapidly opening and closing switch to time the shifting of the rib after each gauging operation, and the amplifier having a switch responsive to the work size for determining the direction of shifting of the rib.

14. In an apparatus of the character indicated, a gauging station from which rollers are successively fed endwise, a gauging member engageable with each roller at the gauging station, a laterally movable selector having a rib between a pair of spaced roller-receiving pockets, the rib being normally in line with a roller at the gauging station to stop the advance of said roller, gauging member controlled mechanism laterally shifting the selector and rib in a selected direction after each gauging operation, said direction of rib movement depending on the size of the gauged roller to bring the selected pocket in line with the gauging station for receiving a roller endwise, and mechanism returning the rib to its normal in line position prior to the next gauging operation and causing the gauged roller to be dropped from the bottom of the selected pocket.
